CLAIM

The ornamental design for a tableware bowl, as shown and described.

DESCRIPTION

FIG. 1 is a top, front, perspective view of a tableware bowl showing my new design;

FIG. 2 is a top plan view thereof;

FIG. 3 is a front elevational view thereof, the rear elevational view being a mirror image thereof;

FIG. 4 is a left side elevation view thereof;

FIG. 5 is a right side elevation view thereof;

FIG. 6 is a bottom plan view thereof;

FIG. 7 is a top, front, perspective view of a tableware bowl showing a second embodiment of my new design;

FIG. 8 is a front elevational view thereof, the rear elevational view being a mirror image thereof;

FIG. 9 is a left side elevation view thereof, the right side elevation view thereof being identical thereto; and,

FIG. 10 is a bottom plan view thereof.
